(57) **CLAIM**

The ornamental design for a hose connector, as shown and described.

DESCRIPTION

FIG. 1 is a front perspective view of a hose connector, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is another perspective view of the hose connector with a hose.

FIG. 9 is another perspective view of the hose connector with a hose.

FIG. 10 is another perspective view of the hose connector with a hose; and,

FIG. 11 is another perspective view of the hose connector with a hose.

The broken lines in the drawings depict environmental structure and boundaries and form no part of the claimed design.
